UNITED STATES PATENT OFFICE.

FRANK M. SHERRILL, OF INDUSTRY, KANSAS.

WEED-CUTTER AND CULTIVATOR.

SPECIFICATION forming part of Letters Patent No. 629,015, dated July 18, 1899.

Application filed December 3, 1898. Serial No. 698,160. (No model.)

To all whom it may concern:

Be it known that I, FRANK M. SHERRILL, a citizen of the United States, residing at Industry, in the county of Dickinson and State 5 of Kansas, have invented certain new and useful Improvements in a Combined Weed-Cutter and Cultivator; and I do hereby declare the following to be a full, clear, and exact description of the invention, such as will enable 10 others skilled in the art to which it appertains to make and use the same.

My invention relates to improvements in combined weed-cutters and cultivators, and is especially designed for use in working listed 15 corn.

The invention embodies the constructions and combinations of parts hereinafter described, and specifically pointed out in the claims.

20 In the accompanying drawings, wherein like letters of reference designate corresponding parts in the several views, Figure 1 is a plan view of a construction embodying my improvements. Fig. 2 is a side elevation.

25 Fig. 3 is a side elevation of one of the supporting-frameworks detached; and Fig. 4 is a sectional view on the line $x-x$ of Fig. 3.

Referring to said drawings, A designates the main frame of the machine, preferably 30 rectangular in shape. This frame may be divided off into any desired number of sections; but for convenience in illustration three are shown, they being designated at B B' B''. These sections are spaced equidistant 35 apart by division-walls C and C', there being two in each instance, with spaces D and D' left between them. The frame A is peculiar in cross-section to afford the greatest possible strength, together with simplicity in construction, and comprises elongated parallel 40 bars E and F, the former occupying a position relatively lower than the plane of the latter, and the connecting side pieces e e', formed with the horizontal enlarged portions

45 f f' and the rearwardly and upwardly extending portions g g'. The division-walls C and C' correspond to the side pieces just referred to.

Mounted on a block E' centrally of the 50 frame on the bar E, rigidly secured to the bar F and extending forwardly in the plane of

the bar F, is the draft-rod G, upon which the seat is mounted in any usual manner. At the extreme forward end of this rod is a bracket G', and pivotally secured in this bracket is a 55 semicircular plate G², having a stem G³, to which the tongue is pivotally secured. The pivot in the bracket shown at x extends downward and terminates in the pintle x'. On an axle passing through this pintle are the lead 60 or guide wheels of the machine. In order that the guide-wheels may be locked in any desired position when the machine is temporarily out of use, a semicircular series of perforations g² are provided in the plate G², and 65 these perforations are adapted to be engaged by a bolt g³, passing through the bracket G'.

H, H', and H² represent the main wheels of the machine and are of the usual type. The central wheels H' are adapted to revolve 70 on a fixed axle h', while the wheels H H² revolve, respectively, on laterally-slidable axles h h².

The object of having the outside sets of 75 wheels slidably mounted is in order that they may adjust themselves to run in furrows varying slightly in distances apart.

The ends of the axles h h² are mounted in 80 spring-boxings J, so as to accommodate for the unevenness of the ground.

Adapted to bear on the under surface of the bar E and rigidly secured on the axles between the wheels of the respective sets are the bearing-blocks K, their inner ends being formed into segments L. To brace these 85 blocks and hold them in proper position, I provide the U-shaped brackets M, pivoted to the axles and secured to a shoulder on the blocks by the inturned lugs m. Rollers m' are secured to the brackets on their outer 90 surfaces and arranged to run on the inner edge of the bar E, and corresponding rollers m² secured to projecting portions of the blocks are adapted to run on the under edge of the bar E.

In order that the weed-cutters and the 95 plows may be held in adjusted positions and operated simultaneously, I provide the following construction: Pivoted on the axles in the respective sections and adapted to engage with the segments L are the levers and spring-pawls l. The bifurcated ends of these levers

are extended some distance downward and are then in turn rigidly secured to the inner upturned ends of the cutter-blades N. Also secured rigidly to these bifurcated portions and having apertured ends fitting over the axles are the bars O. These bars extend rearwardly and constitute part of the framework P, comprising the pivoted outer bars p p' and the connecting-bars p². This framework affords the supporting means for shovels R, which may be of any usual or preferred construction.

From the foregoing description it will be seen that should the furrows in which the machine is working vary slightly in their distances apart the outer frameworks, together with the wheels and cultivating means therein, will readily adjust themselves laterally in their loose bearings, the spaces D D' permitting of such movement, and the frame sliding on the bar E through the medium of the antifriction-rollers before described, and the spring-boxings J of the axles will permit of the vertical adjustment of the same to allow for the unevenness of the ground. When it is desired to adjust the cutters and shovels, all that is necessary is to manipulate the levers and spring-pawl in the direction desired, and the cutter-blades being rigid on said levers, as also the shovels through the framework P, they will both be simultaneously and correspondingly operated in one or the other direction.

While there is shown in the drawings a particular embodiment of the invention for accomplishing the ends desired, it is to be understood that the invention is not thereby necessarily limited to such particular construction, as such is merely shown for purposes of delineation. Other means might be employed for accomplishing the same results.

Having thus described the invention, what is claimed as new, and desired to be secured by Letters Patent, is—

- 45 1. In a cultivator, the combination with a main frame comprising a series of sections, and wheels mounted in said sections in supporting-frames movable laterally and vertically therein, substantially as described.
- 50 2. In a cultivator, the combination with a main frame, wheel-supporting frames mounted in said main frame and laterally self-movable therein, and wheels in said wheel-frames, substantially as described.
- 55 3. In a cultivator, the combination with a main frame, a series of sections in said frame, axles mounted in said sections and movable laterally therein, and wheels on said axles, substantially as described.
- 60 4. In a cultivator, the combination with a frame, an axle laterally movable in said frame, vertically-yieldable bearings therefor, and a wheel and cultivating means on said axle, substantially as described.
- 65 5. In a cultivator, the combination with a main frame, a supporting-framework mounted in said main frame and laterally slidible

automatically therein, and wheels and weed-cutters secured to said framework, substantially as described.

6. In a cultivator, the combination with a main frame, brackets mounted in said frame, and laterally slidible automatically therein, and wheels and plows secured to said brackets immovable laterally relative to the brackets, substantially as described.

7. In a cultivator, the combination with a main frame comprising three sections, a supporting-bracket rigidly mounted in the center section, additional supporting-brackets mounted in the outside sections so as to have lateral movement therein; and cultivating means immovable laterally relative to the brackets supported in and carried by said brackets substantially as described.

8. In a cultivator, the combination with a main frame, a bracket mounted in said frame and laterally self-slidible therein, antifriction-rollers on said bracket, and cultivating means in said bracket, substantially as described.

9. In a combined weed-cutter and cultivator, the combination with a main frame, a supporting-framework in said frame, and self-slidible laterally therein, cutting-blades and plows on said framework, and means in said framework independent of the main frame for adjusting the cutting-blades and plows, substantially as described.

10. In a combined weed-cutter and cultivator, the combination with a main frame, a supporting-framework mounted on an axle self-slidible laterally in said main frame, and plows and cutting-blades simultaneously adjustable in said framework, substantially as described.

11. In a combined weed-cutter and cultivator, the combination with a main frame comprising a series of sections, a series of supporting-frameworks in the respective sections, the outer ones of said series being laterally self-movable in the main frame, wheels in said frameworks, cutting-blades and plows on said frameworks, and means for adjusting the blades and plows, substantially as described.

12. In a cultivator, the combination with a frame, a cultivating device, means for adjusting the cultivating device, means for supporting the cultivating device in the frame and laterally self-slidible therein irrespective of the adjustment of said cultivating device, substantially as described.

13. In a cultivator, the combination with a main frame, a supporting-framework in said frame and slidible laterally therein, cultivating means in said framework, and means in the framework for adjusting the cultivating means, substantially as described.

14. In a cultivator, the combination with a main frame, a supporting-framework, a cultivating device, laterally self-slidible with said framework, and means independent of the main frame for adjusting the cultivating device, substantially as described.

15. In a cultivator, the combination with a main frame, a supporting-framework in said frame and self-movable laterally therein, a cultivating device mounted in said framework, and means in said framework independent of the main frame for adjusting the cultivating device, substantially as described. 5
16. In a cultivator, the combination of a main frame, a supporting-framework mounted in said main frame and laterally self-slidable therein, and guiding and cultivating means mounted in said supporting-frame, substantially as described. 10
17. In a cultivator, the combination of a frame, cultivating means laterally movable therein, and vertically-yielding bearings for said means, substantially as described. 15
18. In a cultivator, the combination with a frame, supporting means in said frame, vertically-yieldable bearings therefor and wheel and cultivating means laterally self-slidable on said supporting means, substantially as described. 20
19. In a cultivator, the combination with a frame, an axle horizontally mounted in said frame, wheel and cultivating means mounted on said axle and laterally self-movable thereon in relation to the frame, substantially as described. 25
20. In a cultivator, the combination with a frame, supporting means in said frame and laterally movable therein, wheels and cultivating means on said supporting means, and adjusting mechanism for the cultivating means on the support intermediate each pair of wheels, substantially as described. 30
21. In a cultivator, the combination with a main frame, an axle in said frame, a supporting-frame mounted on said axle and self-mov- 35
- able laterally therewith, and guiding and cultivating means mounted in said supporting-frame, substantially as described. 40
22. In a cultivator, the combination with a main frame, an axle in said frame, a supporting-frame loosely mounted on said axle and self-movable laterally in relation to the frame, and guiding and cultivating means mounted in said supporting-frame, substantially as described. 45
23. In a cultivator, the combination with a main frame, a supporting-framework therein, guiding and cultivating means mounted on and laterally self-movable with said framework, and bearing against the front bar of the main frame, substantially as described. 50
24. In a cultivator, the combination with a main frame, a supporting-framework therein, guiding and cultivating means mounted and laterally movable with said supporting-framework, and immovable laterally relative to the framework, and antifriction guiding means slidingly engaging the main frame, substantially as described. 55
25. In a cultivator, the combination with a frame, guiding and cultivating means mounted and laterally movable in said frame, a guiding-bracket slidingly engaging the frame, a toothed segment on said bracket, and means adapted to engage said segment to vertically adjust the cultivating means, substantially as described. 60
